UNITED STATES PATENT OFFICE

RUDOLF GRABNER, OF HOHENSTEIN-ERNSTTHAL, GERMANY

KNIT GOODS

Application filed June 5, 1931, Serial No. 542,401, and in Germany June 26, 1930.

The present invention relates to a method of producing double-sided and ladder-proof knit goods which, unlike the known fabrics of this type, retain their elasticity.

According to the present invention, prior defects are eliminated by rendering the goods ladder-proof by drawing the loops of one needle row through the loops of the opposite row before knocking them over. For this purpose, the two needle rows are disposed in a downwardly inclined position exactly opposite one another and not in staggered relation to each other, and the needles of one row are driven out or lowered only after the needles of the opposite row have been knocked over. The lowered needles pass through the loops formed by the opposite needles, and when they have passed through these loops far enough to expose their open latches, they are supplied with thread and drawn back, so that their thread is drawn through the loops of the other needles to form loops. The thread is held very tightly on the needles which will avoid the slipping off or the missing of the needles to enter each loop or to drop a loop, which is a material advantage.

One way of applying the method according to the invention is illustrated in the accompanying drawings, in which Figures 1 to 5 show various steps in the process; Figs. 6 and 7 are, respectively, a side and front view of special parts serving for closing the latches after the latter have caught the thread; Fig. 8 is a top view of the two beds of a knitting machine; Fig. 9 is an oblique view of a plurality of needles arranged side by side to carry out the process; Fig. 10 is a view of the double-sided goods obtained by this method; and Fig. 11 is a view of the loops of a fabric produced by racking the needle beds over a division before starting a course.

The needles of the two needle rows 1 and 2 incline downwardly at an angle of approximately 30° and are moved so that while needles of one row are lowered those of the opposite row are raised, i. e., knocked over. The needles of the two rows 1 and 2 carry, for example, the meshes 3 and 4, and the needles of the two rows 1 and 2 are in knocking over position (Fig. 1). Now, if the

needles of row 1 are lowered, their heads will pass through the loops 4 of the needles of row 2 (Fig. 2), since the needles of both rows are placed exactly opposite one another, and the needles of row 1 continue to move through the loops 4 until their opened latches are in front of the meshes 4, as indicated in Fig. 3. While in this extreme position, the needles of row 1 are supplied with the thread 5 and drawn back, so that the thread 5 is passed through the meshes 4 of the needles of row 2 and formed into loops as on a knitting machine, whereupon the needles of row 1 knock their loops 3 over the looped thread 5 (Fig. 4). At the end of this operation, both rows 1 and 2 are in knocking over position again, but the action of the needles is changed in so far as the needles of row 2 are lowered now and pass through the newly formed loops 6 of the needles of row 1 (Fig. 5) to be supplied with thread by a thread-guide arranged opposite to them and not shown.

If machines having individually movable needles are concerned, such as, for example, flat knitting machines, not all needles of one row will jointly pass through the loops of the other row (Fig. 8) but subsequently one after the other and always at the very moment when the needles of the opposite row have just been knocked over.

The method can be carried out also on machines whose needle rows constitute units as, for example, in double rib warp frames. In this case, one needle bar knocks over first whereupon the opposite needle bar is lowered to pass through the meshes of the first bar. So far as the invention itself is concerned, it is immaterial whether the needles can be moved singly or jointly.

The method could be supplemented in so far as it would be possible to dispose the two needle rows in staggered relation after the completion of a course, so that the needles of one row would pass through the loops of the needles of the opposite row adjacent to the ones penetrated before. This would result in the production of a fabric of the kind shown in Fig. 11, which is even superior to the goods shown in Fig. 10 as to the firmness of the loops produced.

As the latches of the needles passed through the loops as described may not always close automatically during the return of the needles for the reason that the penetrated loops hanging on to their needles are lifted off on top by the penetrating needles, small latch closers (Figs. 6 and 7) may be positioned in an elastic and oscillatory manner above the needles, which embrace the needles and, during the return of the latter, are disposed so that the latches must strike them to be closed thereby. These elastic and oscillatory latch closers 7 may, for example, be secured to the needle beds and controlled by special rods 8 or the like in such a way that they are lifted out of the needles after the latches are closed to prevent interference with the further work of the needles.

I claim:—

- 20 1. A method of producing double-sided knit goods on a hosiery or knitting machine with two downwardly inclined needle rows consisting in lowering at first only the needles of one of the two rows arranged exactly opposite one another when the needles of the opposite row are knocked over, causing the needles of the first row to pass through the meshes of the needles of the other row, supplying the needles of the first row with thread, drawing back the needles of the first row with their thread through the meshes already penetrated by them in order to form loops and in causing the penetrated meshes to be knocked over the loops drawn through them.
- 35 2. A method as claimed in claim 1, according to which one of the two needle rows is racked after the completion of a course and the lowered needles are passed through the meshes of the needles adjacent to the needles of the opposite row.

In testimony whereof I have affixed my signature.

RUDOLF GRABNER.
